By his Attorney,
Nelson M. Howard.

UNITED STATES PATENT OFFICE.

WILLIAM G. DODGE, OF NEWBURYPORT, MASSACHUSETTS, ASSIGNOR TO UNITED SHANK & FINDINGS COMPANY, OF BOSTON, MASSACHUSETTS, A CORPORATION OF MASSACHUSETTS.

MANUFACTURE OF TURN SHOES.

Original application filed May 4, 1921, Serial No. 466,682. Divided and this application filed April 26, 1927. Serial No. 186,739.

This invention relates to improvements in the manufacture of shoes and particularly to improvements in methods of stiffening the shank or arch portions of turn shoes, the 5 present application being a division of my earlier application, Serial No. 466,682, filed May 4, 1921.

A turn shoe is customarily provided with a shank stiffener, frequently called a turn 10 shank, consisting of a stiffener member, commonly called a filler piece, of leather or leatherboard which is shaped to fit within the heel and shank portions of the shoe, and a metallic reinforcing strip which is attached 15 to the lower side of the filler piece. At its heel end the filler piece is commonly secured to the shoe by the heel-attaching nails. The shank portion of the filler piece, or stiffener member, however, is either left entirely un- 20 attached or it is secured in place merely by glue or by a small tack in such a manner that this portion of the filler piece usually becomes detached after the shoe has been worn a short time. When unsecured to the sole the shank 25 portion of the filler piece is capable of moving longitudinally relatively to the sole when the shoe is flexed, as when the wearer is walking. As a result in most turn shoes the shank stiffener cannot be relied upon prop- 30 erly to support and stiffen the arch or shank.

In view of the foregoing, one object of the present invention is to improve the manufacture of turn shoes so as to provide for the desired adequate and permanent stiffening of 35 the shank or arch portions of the shoes.

To the attainment of this object, the invention, considered in one aspect, provides a novel method which, as herein exemplified, consists in securing together the upper and sole of a 40 turn shoe and turning the shoe in the usual manner, locating on the sole of the shoe in a predetermined position within the shoe a composite stiffener unit comprising a reinforcing strip of hardened metal and a filler piece 45 having heel and shank portions shaped to fit the interior of the heel and shank portions of the shoe, the stiffener unit having a fastener-receiving hole extending through both the filler piece and the reinforcing strip, 50 utilizing the wall of the hole in the stiffener unit as a positioning surface in determining the location in the sole of a fastener for securing the stiffener unit to the sole, and pass-

ing a fastener inwardly from the outside of the shoe through the sole and through the 55 stiffener unit.

To facilitate the incorporation of shank stiffeners in turn shoes in the manner above stated, the invention, considered in another aspect, comprises as herein exemplified, 60 forming a filler piece, blanking and punching a hole through a metallic reinforcing strip, attaching the reinforcing strip to the filler piece to provide a reinforced shank stiffener, thereafter forming in the filler piece 65 a hole similar to and registering with the hole in the attached reinforcing strip, placing the reinforced shank stiffener in a turn shoe, and utilizing the registering holes in the filler piece and the reinforcing strip to determine the 70 location in the shank portion of the sole of a fastener for securing the shank piece to the sole.

The invention will be explained with reference to the accompanying drawings, in 75 which

Fig. 1 is a diagrammatic plan view of a metal strip from which a plurality of reinforcing strip blanks have been cut;

Fig. 2 is a plan view of a reinforcing strip 80 blank;

Fig. 3 is an end view of the blank;

Fig. 4 is a view, partly in section and partly in elevation, illustrating the shaping of the blank;

Fig. 5 is a side elevational view, partly in section, of the shank stiffener showing the leather stiffener member or filler piece with a metallic reinforcing strip made fast thereto;

Fig. 6 is a longitudinal section through a 90 turn shoe in which the improved shank stiffener is incorporated; and

Fig. 7 is a plan view of a metal strip from which has been cut a plurality of reinforcing strip blanks of modified form.

In Fig. 1 of these drawings is shown a strip 1 of hardened metal, for example tempered steel such as that commonly employed for making shank stiffeners for turn shoes. The strip 1 is subjected to a blanking operation 100 whereby it is cut at intervals therethrough to form individual reinforcing or stiffening strip blanks 2. Each blank terminates at its ends in prongs 3 and is punched or perforated at 4, preferably but not necessarily in the cutting operation. Each blank is formed,

for example, between dies as shown in Fig. 4, the prongs 3 being bent or struck up at the desired angle and the central portion of the strip being curved to conform to the longitudinal curvature of the shoe shank and having a central longitudinal stiffening rib 5 formed therein. In Fig. 5 there is shown at 6 a shoe bottom member consisting of a piece of leather, leatherboard or other suitable material, which is shaped to conform to the heel and shank portions only of the inside of the tread sole of a shoe and which has a thin skived forward end 7. The illustrated member 6 constitutes a stiffener member or filler piece of the type ordinarily reinforced by a metallic reinforcing or stiffening strip to form what is commonly known as a "turn shank" or "shank stiffener for turn shoes". The invention, however, is not necessarily restricted to operating upon shank stiffeners for turn shoes but is applicable also in connection with the manufacture of shoes of other types such, for example, as McKay sewed shoes, wherein it is desired to secure together a bottom member, such as an insole, a reinforcing strip and a tread sole.

The metal reinforcing strip which is made from the blank 2 is made fast between the ends of the filler piece 6 by means of the prongs 3, which are driven and clinched therein. The prongs 3 serve to maintain the strip 2 and the filler piece 6 in assembled relation with the perforations 8 and 9 in registration so as to facilitate the insertion of a rivet or other fastener through them after they have been placed in a shoe. The filler piece 6 is then perforated at 8 in alignment with the hole 4, thus completing the making of the shank stiffener and providing a shank stiffener unit which is ready to be incorporated in a shoe. Next, the stiffener unit, consisting of the filler piece 6 and the metal reinforcing strip, is placed in position in a turn shoe, as shown in Fig. 6, and the sole of the shoe is perforated at 9 in alignment with the registering holes 4 and 8 and substantially centrally of the shank portion of the sole, the exact location of the hole in the sole being thus determined by the location of the registering holes in component parts of the shank stiffener. A rivet 10 is passed through the hole in the sole and through the holes in the parts of the shank stiffener unit and is clinched at 11 within the shoe. Thus it will be seen that the wall of the hole in the shank stiffener unit serves as a positioning surface in determining the location in the sole of the rivet or other fastener. The forward end portion of the filler piece may be made fast to the sole by any suitable securing means, and the rear end of the filler piece may also be made fast to the sole by means such as the heel attaching nails 12.

The modified form of reinforcing strip blank shown in Fig. 7 is designed for the pur-

pose of decreasing the waste in the blanking or cutting out of the metal reinforcing strip. In this case prongs 3', corresponding to the prongs 3, are made at one end of the metal blank, and prongs 3'a are formed at the other end of this blank, the prongs 3'a of one blank nesting within the prongs 3' of the adjacent blank. By this means the waste from the cutting of the prongs is much reduced and the number of blanks which may be cut from a long strip of stock somewhat increased. In other respects the construction is the same as before described.

By constructing a turn shank stiffener and incorporating it in a turn shoe as herein described, there has been produced a turn shoe having a firmly supported and adequately stiffened shank or arch. Both the filler piece and the metal reinforcing strip are rigidly secured to the shank of the sole, a result which has not heretofore been accomplished so far as the inventor is aware. The assembly and securing together of the parts of the shank stiffener and also the incorporating of the stiffener in a shoe may be conveniently and expeditiously practised. This will be apparent when it is realized that the fastener-receiving perforation 8 in the filler piece is initially formed in alignment with the perforation 4 in the reinforcing strip and also that the perforation 9 in the sole of the shoe is initially formed in alignment with the aligned perforations 4 and 8 in the reinforcing strip and filler piece. Consequently when the filler piece and the reinforcing strip are being assembled, and later when the stiffener unit composed of these two parts is being assembled with the sole of the shoe, it is unnecessary to waste time by bringing into registration fastener-receiving perforations originally made out of registering relation in the various parts. Furthermore, the arrangement is such that the herein described fastening means permanently and rigidly secures the stiffener unit and the sole in assembled relation to preserve the arch at the shank of the shoe.

Having thus described my invention, what I claim as new and desire to secure by Letters Patent of the United States is:

1. That improvement in the art of making turn shoes which consists in forming a filler piece, blanking and punching a hole through a metallic reinforcing strip, forming said strip to the longitudinal curvature of a shoe shank, attaching the strip to the filler piece to form a shank stiffener, punching a hole through the filler piece in alignment with the hole in the reinforcing strip, positioning the shank stiffener within a turn shoe, making a hole through the sole of the shoe in alignment with the aligned holes in the shank stiffener, and fastening the shank stiffener in position by a rivet passed through the holes in the sole and the shank stiffener.

2. That improvement in the art of making turn shoes which consists in securing together the upper and the sole of a turn shoe and turning the shoe in the usual manner, locating on the sole of the shoe in a predetermined position within the shoe a composite stiffener unit comprising a reinforcing strip of hardened metal and a filler piece having heel and shank portions shaped to fit the interior of the heel and shank portions of the shoe, the stiffener unit having a fastener-receiving hole extending through both the filler piece and the reinforcing strip, making a hole through the sole while utilizing the wall of the hole in the stiffener unit as a positioning surface to determine the location of the hole in the sole, and thereafter securing said stiffener unit to the sole by passing a fastener inwardly from the outside of the shoe through the holes in the sole and in the stiffener unit.
3. That improvement in the art of making turn shoes which comprises forming a filler piece, blanking and punching a hole through a metallic reinforcing strip, attaching the reinforcing strip to the filler piece to provide a reinforced shank stiffener, thereafter forming in the filler piece a hole similar to and registering with the hole in the attached reinforcing strip, placing the shank stiffener in a turn shoe, and utilizing the registering holes in the filler piece and the reinforcing strip to determine the location, in the shank portion of the sole, of a fastener for securing the shank piece to the sole.
4. That improvement in the art of making turn shoes which comprises forming a filler piece, blanking and punching a hole through a metallic reinforcing strip, attaching the reinforcing strip to the filler piece to provide a reinforced shank stiffener, thereafter forming in the filler piece a hole similar to and registering with the hole in the attached reinforcing strip, and securing the shank stiffener to the sole of a shoe by passing a fastener inwardly through the sole of the shoe and through the alined holes in the shank stiffener.
5. That improvement in the art of making turn shoes which consists in securing together the upper and sole of a turn shoe and turning the shoe in the usual manner, locating on the sole of the shoe in a predetermined position within the shoe a composite stiffener unit comprising a reinforcing strip of hardened metal and a filler piece having heel and shank portions shaped to fit the interior of the heel and shank portions of the shoe, the stiffener unit having a fastener-receiving hole extending through both the filler piece and the reinforcing strip, utilizing the wall of the hole in the stiffener unit as a positioning surface in determining the location in the sole of a fastener for securing the stiffener unit to the sole, and passing a fastener inwardly from the outside of the shoe through the sole and through the stiffener unit.
6. That improvement in methods of making shoes which comprises providing a fastener-receiving hole in a shank reinforcing strip, attaching the reinforcing strip to a shoe bottom member in predetermined relation thereto, then forming through said member a hole registering with the hole in the reinforcing strip, and thereafter securing said strip and said member to the sole of a shoe by a fastener while utilizing the holes in said member and said strip to locate said fastener relatively to said sole.

In testimony whereof I have signed my name to this specification.

WILLIAM G. DODGE.
